DESIGN FOR A DRILL PRESS PULLEY GUARD

James F. Barnes and Jean O. Reinecke, Chicago,
Ill., assignors to The Delta Manufacturing
Company, Milwaukee, Wis., a corporation of
Wisconsin

Application May 24, 1937, Serial No. 69,531

Term of patent 7 years

To all whom it may concern:

Be it known that we, James F. Barnes and Jean O. Reinecke, both citizens of the United States, residing in Chicago, in the county of Cook and State of Illinois, have invented a new, original, and ornamental Design for Drill Press Pulley Guards, of which the following is a specification, reference being had to the accompanying drawing, forming part thereof.

In the drawing,

Fig. 1 is a front elevation of a drill press pulley guard showing our new design;

Fig. 2 is a side elevation;
Fig. 3 is a top plan view;
Fig. 4 is a bottom perspective view, and
Fig. 5 is a sectional view taken along the line
5—5 of Fig. 3.

We claim:

The ornamental design for a drill press pulley
guard, as shown.

JAMES F. BARNEs.
JEAN O. REINECKE.
